CLAIM

The ornamental design for a shoe sole, as shown and described.

DESCRIPTION

FIG. 1 is a front perspective view of a shoe sole showing my new design;

FIG. 2 is a bottom view thereof; and

FIG. 3 is a rear perspective view thereof.

FIG. 4 is a front view thereof;

FIG. 5 is a rear view thereof;

FIG. 6 is a front lateral perspective view thereof;

FIG. 7 is a lateral side view thereof;

FIG. 8 is a medial side view thereof;

FIG. 9 is a front perspective view of a shoe sole showing an alternative embodiment of my new design;

FIG. 10 is a bottom view thereof;

FIG. 11 is a rear perspective view thereof;

FIG. 12 is a front view thereof;

FIG. 13 is a rear view thereof;

FIG. 14 is a front lateral perspective view thereof;

FIG. 15 is a lateral side view thereof; and,

FIG. 16 is a medial side view thereof.

The broken lines immediately adjacent to the shaded area represent unclaimed boundaries of the design. The broken lines showing the remainder of the shoe represent unclaimed subject matter and form no part of the claimed design.
